CHEST SUPPORTED FIREARM

Melvin A. Elkins, Tucumcari, N. Mex., assignor
of one-half to Nesby W. Sharp, Conchas Dam,
N. Mex.

Application March 9, 1937, Serial No. 129,911

7 Claims. (Cl. 42—1)

This invention relates to firearms and particularly to a firearm designed to be worn upon the chest of a person and fired by a motion of the arms.

5 The firearm which I have devised is particularly intended to be worn by watchmen, bank messengers, mail clerks, and those who are fearful of being or are likely to be held up.

The usual initial command of a bandit is 10 "hands up" and one of the objects of the present invention is to provide a concealed firearm supported on the chest of the wearer beneath the clothing, which will be "fired" upon an upward movement of one hand, the other hand, or both.

15 Another object is to provide a safety means for latching the mechanism against firing action and which must be released before the arm can be fired.

Other objects will appear in the course of the 20 following description.

My invention is illustrated in the accompanying drawings wherein:

Figure 1 is a face view of a firearm constructed in accordance with my invention;

25 Figure 2 is a longitudinal section on the line 2—2 of Figure 1;

Figure 3 is a longitudinal section on the line 3—3 of Figure 1;

30 Figure 4 is a face view of the rear section, the front section being removed;

Figure 5 is a vertical section on the line 5—5 of Figure 2.

In these drawings, 10 designates a rectangular front section of the gun and 11 the back section. 35 These sections are detachably held to each other by screws. The gun formed of the connected sections is supported on the chest by arm-pit straps 12, which buckle in the back, and by straps 13 which extend over the shoulders and across 40 the back like suspenders, and may be attached to the waistband of the trousers.

The front section 10 is flat on its inside face and may be convexly curved on its outer face but is formed to provide an upper set of cartridge 45 chambers and a lower set. Each chamber is designated 14. Engaged in each chamber is a removable adapter 15, each adapter being formed to receive a cartridge of a certain calibre, thus one adapter will receive a 32-calibre cartridge, and another will receive a 16-calibre cartridge, etc. The adapters may be changed to suit the 50 calibre of cartridges desired to be used. I have illustrated two rows of cartridge chambers, one disposed below the other, but obviously my device is adapted to use either one or more sets of

cartridge chambers. The front section 10 is held to the rear section by screws or any other suitable means.

The rear section 11 has a flat outer face and a 5 concavely curved inner face to approximately conform to the curvature of the chest. Extending inward from opposite ends of section 11 are the bores or chambers 15 and 16. The chamber 15 is at a higher level than 16, because of the fact that the two sets of cartridge chambers are disposed at different levels. The same mechanism is used for firing each set of cartridges and, therefore, a description of one set of mechanisms will be equally descriptive of the other.

Extending longitudinally parallel to but in 15 front of and intersecting each chamber 15 is a slot or guideway 17, and disposed at right angles to each slot 17 are a plurality of firing pins 18 equal in number to the cartridge chambers, in 20 that row or set. These are supported by springs 19 mounted upon a plate 20 attached to the section 11 by the screws 20a.

Disposed within each slot 17 is a slide rod or plunger 21 having on its underface a plurality of cam projections 22. At its outer end, each 25 plunger is carried by a head 23, each head being disposed within the corresponding chamber 15 or 16. A light compression spring 24 in this chamber 15 urges the head inward and then yieldingly holds the plunger at the inner end of 30 its stroke with the cams 22 projected beyond the firing pins 18. The spring bears at its outer end against a plug 25. Attached to each head 23 and extending out through the plug 25 is a rod 26 terminating in a ring 26a.

35 Mounted within the respective chambers 27 at opposite ends of the section 11 are the sears 28, each sear being mounted for vertical movement and being capable of being disposed immediately in advance of the corresponding head 23 to hold 40 this head in a retracted position against the action of the corresponding spring 24. Each sear 28 is pivoted to a lever 29 constituting a trigger, the lever being pivoted on a pin 30. The weight of the longer arm of lever 29 is sufficient to raise 45 the sear into its latching position, but a spring might be used for this purpose. From each trigger 29 a cord 31 extends to the corresponding wrist of the wearer or to the wristband of his shirt or coat, thus when the cord 31 is pulled upon by the action of lifting the arm, the corresponding sear is released from its latching engagement with the head, the head is projected 50 by the spring 24, and the cam projections 22 55

force the firing pins inward, thus exploding the cartridges.

Disposed in longitudinally extending bores in the section 11, these bores opening into the chambers 27, are the safety latches 32. These are projected by the springs 33 into engagement with shoulders carried by the sears and thus hold the sears against downward movement, that is, movement away from the firing mechanism. Each safety latch 32 is connected by a link 34 to a releasing rod 35 extending upward through a bore in the section 11 and terminating in an eye which may be connected by a cord 36 to the necktie.

5 In all the figures I have shown the plungers 21 as having been fully projected and as having fired the cartridges in the cartridge chambers 15, it being understood, of course, that in Figures 2 and 3, if the cartridges had not been fired, 10 the plungers 21 would be retracted as would be the heads 23, and that in Figure 5, the sears 28 would, under these circumstances, be projected in front of the heads 23.

The operation of the device, assuming that it 5 is supported on the chest of the wearer, is as follows:

Of course, the "gun" is entirely concealed by the clothing and the cartridge chambers are previously loaded. Normally, the plungers 21 are retracted and held in retracted position against accidental movement out of engagement with the plungers by the latches 32 of the safety means. If now the cord 36 be pulled, the latches are withdrawn from their "safety" position and the 5 trigger levers are free to move. Now if one or both arms are raised, the cord or cords 31 attached to the wristbands of the coat or shirt will pull the sears out of engagement with the corresponding head, the springs 24 will project the 10 plunger and the cam projections will engage the firing pins, projecting them against and discharging the cartridges.

While I have illustrated the cam projections 22 as being equi-distantly spaced along the 5 plunger 21, it is to be understood that these cam projections need not be equi-distantly spaced but may be disposed so that they will operate successively so that the cartridges may be discharged successively from any one row.

10 Preferably the cord 36, as before stated, will be attached to the necktie, the tie being manually pulled upward preparatory to firing the gun. The necktie may be pulled upward as if accidentally, at the time when the hands are being 15 raised, this action, of course, releasing the safety latches 32. It is to be understood, however, that this cord 36 might be attached to any portion of the clothes of the user which will be raised or pulled upward, either intentionally or upon the 20 upward movement of the arm or arms. Inasmuch as in case of a "hold-up", the victim is usually confronted by the bandit at very short range, there will be no necessity of aiming the gun.

5 What is claimed is:—

1. A firearm of the character described, including a body adapted to be supported on the chest, a cartridge holding chamber formed in the body and opening toward the front of the 10 body, a firing pin disposed behind the chamber, a plunger disposed behind the rear end of the cartridge chamber and having a cam projection engaging with the firing pin to project it, a sear operatively engaging said plunger and holding it 15 with its cam projection out of engagement with

the firing pin, a spring urging the plunger in a direction to engage the cam projection with the firing pin, and a cord operatively engaged with the sear and adapted to be connected to the arm of the wearer, an upward movement of the arm 5 placing the cord under tension, releasing said sear and allowing the projection of the firing pin.

2. A firearm of the character described, including a body adapted to be supported on the chest, a cartridge holding chamber formed in the body and opening toward the front of the body, a firing pin disposed behind the chamber, a plunger disposed behind the rear end of the cartridge chamber and having a cam projection engaging with the firing pin to project it when 15 the plunger is shifted in one direction, a sear operatively engaging said plunger and holding it with its cam projection out of engagement with the firing pin, a spring urging the plunger in a direction to engage the cam projection with the 20 firing pin, a cord operatively engaged with the sear and adapted to be connected to the arm of the wearer, an upward movement of the arm placing the cord under tension, releasing said 25 sear and allowing the projection of the firing pin, and releasable means for holding the plunger from operation by the spring.

3. A firearm of the character described, including a body adapted to be supported on the chest, a cartridge holding chamber formed in the body 30 and opening toward the front of the body, a firing pin disposed behind the chamber, a plunger disposed behind the rear end of the cartridge chamber and operating in a plane at right angles to the axis of the firing pin and having a cam projection 35 engaging with the firing pin to project it, a sear operatively engaging said plunger and holding it with its cam projection out of engagement with the firing pin, a spring urging the plunger in a direction to engage the cam projection with 40 the firing pin, a cord operatively engaged with the sear and adapted to be connected to the arm of the wearer, an upward movement of the arm placing the cord under tension, releasing said 45 sear and allowing the projection of the firing pin, releasable and means for holding the plunger from 50 operation by the spring, comprising a spring projected safety pin operatively engageable with the sear to prevent its retraction, and a member flexibly engaged with said pin to retract it upon a pull 55 on the member.

4. A firearm of the character described, including a body adapted to be supported on the chest and formed of an outer section and an inner section detachably engaged with each other, the outer section having a plurality of cartridge chambers and opening through the front of the outer, section, the inner section carrying a plurality of firing pins disposed one behind each of the cartridge chambers and projectible thereinto, a 60 plunger extending at right angles to the firing pins and having a plurality of cam projections adapted to engage the firing pins and project them, a spring urging the plunger in a direction to carry its cam projections against the firing 65 pins, a sear adapted to operatively engage the plunger to hold it in its retracted position against the action of the spring, a trigger operatively engaged with the sear, and a cord extending from the trigger and adapted to be connected to the 70 body of the wearer.

5. A firearm of the character described, including a body adapted to be supported on the chest and formed of an outer section and an inner section detachably engaged with each other, the out- 75

er section having a plurality of cartridge chambers and opening through the front of the outer section, the inner section carrying a plurality of firing pins disposed one behind each of the cartridge chambers and projectible thereto, a plunger extending at right angles to the firing pins and having a plurality of cam projections adapted to engage the firing pins and project them, a spring urging the plunger in a direction to carry its cam projections against the firing pins, a sear adapted to operatively engage the plunger to hold it in its retracted position against the action of the spring, a trigger operatively engaged with the sear, a cord extending from the trigger and adapted to be connected to the body of the wearer, a safety pin mounted in the rear section, a spring projecting the pin into operative engagement with the sear to hold the sear from retraction under the action of said cord, and means connected to the safety pin whereby it may be retracted.

6. A firearm of the character described, adapted to be supported upon the chest of a wearer and having a front section and a rear section detachably connected to each other and the front section having two sets of cartridge chambers therein, the cartridge chambers of each set being disposed in transverse alinement, a plurality of firing pins mounted in the rear section in alinement with the several chambers and adapted to be projected into engagement with the cartridges in said chambers, a longitudinally movable plunger disposed behind each series of firing pins, each plunger having a plurality of cam projections acting to project the firing pins when the plunger is moved in one direction, the rear section having two longitudinally extending chambers, a head mounted in each chamber and connected to the corresponding plunger, springs disposed in said chambers and urging the heads in a direction to carry the plungers against the firing pins, each head having a shank extending out through the end of the section whereby the head may be manually retracted, a pair of sears, one for each head and carried in the rear section and adapted, when moved in one position, to engage in front of the head and prevent the projection of the head in

the corresponding plunger, a trigger for each sear pivoted within the rear section and extending out laterally thereof, and cords extending from the triggers and adapted to be connected to the wrists of the wearer.

7. A firearm of the character described, adapted to be supported upon the chest of a wearer and having a front section and a rear section detachably connected to each other and the front section having two sets of cartridge chambers therein, the cartridge chambers of each set being disposed in transverse alinement, a plurality of firing pins mounted in the rear section in alinement with the several chambers and adapted to be projected into engagement with the cartridges in said chambers, a longitudinally movable plunger disposed behind each series of firing pins, each plunger having a plurality of cam projections acting to project the firing pins when the plunger is moved in one direction, the rear section having two longitudinally extending chambers, a head mounted in each chamber and connected to the corresponding plunger, springs disposed in said chambers and urging the heads in a direction to carry the plungers against the firing pins, each head having a shank extending out through the end of the section whereby the head may be manually retracted, a pair of sears, one for each head and carried in the rear section and adapted, when moved in one position, to engage in front of the head and prevent the projection of the head in the corresponding plunger, a trigger for each sear pivoted within the rear section and extending out laterally thereof, cords extending from the triggers and adapted to be connected to the wrists of the wearer, the triggers projecting beyond the sears, safety latches carried in the rear section, springs projecting said latches into engagement with the projecting ends of the sears to prevent the retraction of the sears, a vertically extending rod mounted within the rear section and having linked connection to said safety latches, and a cord extending from said last named rod and adapted to be connected to the clothing of the wearer.

MELVIN A. ELKINS.
